UNITED STATES PATENT OFFICE.

HERMAN EDWARD BEYER, OF BIRMINGHAM, ALABAMA.

CONDENSER.

1,041,954.

Specification of Letters Patent. Patented Oct. 22, 1912.

Application filed October 18, 1911. Serial No. 635,342.

To all whom it may concern:

Be it known that I, HERMAN EDWARD BEYER, a citizen of the United States of America, residing at Birmingham, in the county of Jefferson and State of Alabama, have invented certain new and useful Improvements in Condensers, of which the following is a specification.

This invention relates to the condensation 10 of steam and other vapors and to apparatus therefor.

It has for its object the obviating of a defect associated with the use of counter-current condensers, occurring whenever such 15 operate at their maximum efficiency. This defect is described in Weiss' Patent No. 496,761, dated May 2nd, 1893, as a shifting from counter-current to parallel-current condensation, whenever the counter-current 20 condensation reaches the state where the temperature in the condensing chamber becomes equal to the temperature of the hot water running off, or in other words, where the pressure in the condenser falls to the 25 point at which the hot water in the waste pipe will boil. The condensation will then shift to a parallel-current condensation, passing over into a water separator provided for the purpose, this water separator being 30 furnished with a barometric leg to permit of the withdrawal of the water running over thereinto.

To automatically return the condensation to counter-current again, Weiss provides 35 means for admitting air or steam into the condensing system so as to lower the vacuum therein, thus creating a difference in the temperature of the hot water running off and the vacuum in condenser chamber, which 40 causes the condensation to return to the counter-current state. The admission of air acts to gradually restore a balanced pressure condition between the condenser and the separator, and as a result of this the normal 45 counter-current condensation will be restored. In view of the fact however that this balancing must take effect through the single connecting pipe between the condenser and separator, which under parallel current 50 condensation conditions is flushed with water and therefore largely closed, it follows that the restoration of the vacuum in condensing chamber to its previous or normal condition will be necessarily slow. It is 55 further true that the admission of air is a

most unsatisfactory means to attain the ends in view by reason of the fact that it adds largely to the work required of the air pump which is necessarily used in counter-current condensers and the sole duty of 60 which is to remove the air. It will be evident that when a balanced condition as to pressure exists between the condenser and the separator, gravity will prevent any tendency of the water to flush over from the 65 condenser into the separator and therefore my object is to effectively maintain a balanced condition as to pressure between the condenser and separator, and to this end I provide, in addition to the upper connection 70 between separator and condenser for air removal as disclosed in the Weiss condenser and other counter-current condensers, a supplemental connection leading from the lower end of the condenser and preferably from 75 below a false bottom therein into the lower part of the separator. The air pump will thus have a direct connection both to the upper end and the lower end of the condenser, and it follows that under abnormal 80 operating conditions when the parallel current condition is set up, the tendency of the water to flush and fill the upper connection between separator and condenser will not interfere with the rapid balancing of the 85 pressures through the lower pipe connection which remains open and uninterrupted. It is in this respect that my invention essentially differs from all other types of counter-current condensers. 90

A further object of my invention is to protect the air pump from hot water or steam in the air drawn off through the lower connection between condenser and separator 95 and from the steam that tends to rise from the boiling over of the condenser and from the hot water in the barometric leg of the separator. To this end I interpose a valve which is automatically closed by the flushing action of the water to cut off the air pump from the condensing system. I also provide a special cooling spray in the separator through which all air and vapors drawn off from condensing space through 100 the lower connection must pass before entering the pipe leading to the air pump. 105

My invention further comprises the details of construction and arrangement of parts which in their preferred embodiment are hereinafter more particularly described 110

and claimed with reference to the accompanying drawings, in which:—

Figure 1 is a vertical sectional view through the condenser and separator. Fig. 2 is a detail view showing the arrangement of the spray nozzle in the water separator. Fig. 3 is a sectional view of the condensing apparatus operating as a counter-current condenser. Fig. 4 is a similar view showing that apparatus under conditions of parallel-current operation with the connection to the air pump interrupted.

Similar reference numerals refer to similar parts throughout the drawings.

In the preferred embodiment of my invention which is illustrated in the accompanying drawings, but to the details of which I do not desire to be limited, I show a metallic condenser body 1 having any suitable shape, and admit the steam or vapor to be condensed through an inlet pipe 2 which is provided with a downwardly opening discharge orifice which causes the steam or vapor to enter the condenser body at or near the center with a downward direction of flow. The condenser body is provided at its upper end with a water reservoir 3 which communicates with the condenser body through a central opening surrounded by a weir 4. Water is admitted to the chamber 3 through a water inlet 5 and under normal operating conditions tends to flow therefrom into the condensing chamber over the edges of the weir 4 and in addition through an opening 6 into a descending pipe 7 which communicates with a nozzle 8 disposed in the water separator 9. The water chamber is provided with an air outlet pipe 10 near its upper end which opens into the upper end of the water separator 9. A pipe 11 is disposed in the upper end of the separator 9 and passes through a partition 12 at the top of the water separator. Preferably this pipe is provided with an off-set 13 so that it is supported by the partition 12 and it is normally open top and bottom. The upper end of the pipe 11 opens into a valve chamber 14 in which I provide a conical valve 15 mounted on a rod 16 and suitably held in place thereon, the upper end of the rod projecting through an opening in the cover 17 of the valve chamber and being connected at its top end to a spring-receiving cap 18. This cap receives a coil spring 19 which is seated on the cover 17 and tends normally to hold the valve 15 in the position shown in Fig. 1. The spring is housed in an air tight casing 20. A nozzle 21, at the side of the valve chamber 14, is adapted to be connected by the air pipe 22 to any desirable type of suction pump 23, having an air discharge port 38. The lower end of the rod 16 passes through a central opening in a spider 24 fixed in the upper end of a bucket 25, suitable fastening means being applied to the

rod to attach the bucket thereto. I provide the bottom of the bucket with a drainage opening 26.

The condenser body 1 is supported by a flange 27 on a cone 29 which is in turn supported by a barometric waste pipe 36 (Figs. 3 and 4) extending into a hot well 35. The condenser body terminates in a false bottom formed by a cone 28 (Fig. 1) through the opening 30 in which the waste hot water passes from the condenser into the cone 29 and then into the waste pipe 36. The false bottom 28 being concentric with but smaller than the cone 29 and projecting into it, an annular chamber 31 is formed from which a pipe 32 leads to the water separator 9 at a point below the spray nozzle 8 disposed in the lower portion of said separator. The separator terminates at a point below the connecting pipe 32 in a cone 33 supported on a barometric waste pipe 34 also extending into the hot well 35 from which the waste water runs by means of an opening 37.

The pipes 10 and 32, which form connections between the condenser body 1 with the water separator 9, give simultaneous access to the aspirating action of the air pump to the top of the condenser body and to the chamber 31.

Referring to Fig. 3, the normal operation of counter-current condensation is shown. The cooling water entering chamber 3 and flowing over the edges of the weir 4 condenses the steam or vapor entering through nozzle 2. The descending water will also, due to its velocity, carry through the opening 30 and into chamber 31 a portion of the air and incondensable gases which enter with the steam or vapor, from which chamber 31 they are immediately removed by the aspirating action of the air pump. A small portion of the cooling water from chamber 3 will flow by means of the pipe 7 into the spray nozzle 8, and this water, as it flows downward from the nozzle 8 through the lower end of separator 9 and waste pipe 34 into hot well 35, will cool this air that is withdrawn from chamber 31. This cooling is made necessary due to the air having been in contact with the hot water running out of the main waste pipe 36, and this air will mix with the air entering the separator 9 through nozzle 10, so that all of the air will travel through the pipe 11 and from there into the air pump 23 by means of air suction pipe 22, being discharged into the atmosphere through port 38.

Should the condensation shift to the water separator 9, as shown in Fig. 4, the water will flow over into 9 through pipe 10 and will then fill the bucket 25, which by its weight, when so filled, overcomes the resistance of the spring 19 and moves the valve 15 to close the top of pipe 11. The closing of the top of pipe 11 prevents any steam,

hot air or water entering pipe 22 so that the air pump is protected from damage and the uninterrupted connection afforded by pipe 32, will, in the nature of things, 5 rapidly balance the pressure between 1 and 9. This balance thus restored, the condensation will surely and promptly return to the chamber 1 and thus stop the water running over into chamber 9. The bucket 25 will 10 quickly drain itself of its weight of water so that the spring 19, aided by the suction action of the air pump on the valve 15, will surely and quickly open the valve 15 again, and automatically put the air pump in connection with the condensing system so that 15 the condensation can be conducted in its normal manner throughout the condensing system, as shown in Fig. 3. Because of the cooling water spray at 8, no hot air can 20 enter the air pump directly after the condensation has been returned to chamber 1.

By the means as above described, I improve on the methods employed for shifting back to counter-current condensation from 25 parallel-current condensation when such has occurred in counter-current condensers, enabling a quick recovery of the vacuum in condenser 1.

In place of the valve 15 as shown, I may 30 use any other suitable closing device, such as a cock, a slide valve or the like which is closed automatically by the transfer of the condensation from the condenser to the separator.

35 In place of the spring 19, I may use any other suitable opening device or means to be used in connection with the pail or automatic closing means. Any suitable means may be utilized for drawing out the air and 40 incondensable gases through the pipe 32, though it is preferable to utilize a single pump having a double connection to the condenser to exert the aspirating effect at both ends in the manner described.

45 As hereinbefore stated the construction of various parts of my apparatus may be widely varied within the scope of my invention which I consider to broadly cover the utilization of suction means to draw off said 50 air and incondensable gases both from the upper and lower ends of the condensing chamber of a counter-current condenser.

Having thus described my invention, what I claim as new and desire to secure by Letters Patent, is:—

1. In a counter-current condenser, the combination of a condensing chamber, a water separating chamber, means to connect the upper and lower ends of said separating 60 and condensing chambers, and an air suction apparatus connected with the condensing system.

2. In a counter-current condenser having a vapor admission port, a water chamber 65 above the port, means to provide an air

chamber below said port, a water separator, pipe connections from the water chamber to the separator and from said air chamber to the separator, substantially as described.

3. In a counter-current condenser having 76 a condensing chamber and an air suction apparatus, the combination therewith of means to connect said air suction apparatus to the upper and lower ends of the condensing chamber, as and for the purposes described. 77

4. In a counter-current condenser having 81 a condensing chamber, a water separating chamber, and an air suction apparatus, the combination therewith of conduits connecting said water separator to the upper and lower ends of the condensing chamber, and means to cool the air and vapors which flow from the lower end of the condenser through said lower conduit to the air suction apparatus, substantially as described. 82

5. In a counter-current condenser comprising a condensing chamber having a false bottom at its lower end and a water chamber at its upper end, means to discharge the vapor to be condensed into said condensing chamber at an intermediate point, a water separator having an upper connection to the water chamber and a lower connection to the space below said false bottom, and aspirating means connected to said separator, 91 substantially as described. 92

6. In a counter-current condenser, a condensing chamber, an aspirating means connected to the lower end of said chamber where hot air tends to collect, and means to 10 cool said air in its passage from said chamber to said aspirator, for the purposes described.

7. In a counter-current condenser comprising a condensing chamber having a water chamber in its upper end, a separating chamber having its upper end connected to said water chamber, a spray in said separator, means to deliver water from said water chamber to said spray, a connection below said spray to the lower portion of the condensing chamber, barometric water legs connected to said condensing and separating chambers, and air suction means connected to the upper end of said separator, substantially as described. 111

8. In a counter-current condenser, a condensing chamber having an air outlet port at its upper end, a barometric water leg connected to the bottom of said chamber, a 124 false bottom in said chamber, an air chamber formed between the bottom and false bottom of said separating chamber, and means to exhaust the air from said air chamber. 125

9. In a counter-current condenser, a condensing chamber, a separating chamber, an upper pipe connecting said chambers, a lower pipe connecting said chambers, an air suction pipe leading from the separator, a 130

valve for closing said pipe, means controlled by the flushing of water through the upper pipe into the separator for temporarily closing said valve, and means to open said valve when the flushing of water stops, substantially as described.

10. In a counter-current condenser, means to connect a suction apparatus with the upper and lower ends of the condenser, and
10 means to temporarily interrupt the suction

effect of said apparatus in the condenser under conditions of parallel-current condensation.

In testimony whereof I affix my signature in presence of two witnesses.

HERMAN EDWARD BEYER.
